HEAD OF A GOLF CLUB

Minden Vaughan Blake, Carnanton, Woodlands Road
E., Virginia Water, Surrey, England

Filed Feb. 10, 1969, Ser. No. 15,720

Term of patent 14 years

Claims priority, application Great Britain Sept. 9, 1968

Int. Cl. D21—03

U.S. Cl. D34—5

I claim:

The ornamental design for a head of a golf club, substantially as shown.
